(57) **CLAIM**

The ornamental design for a combination ceiling fan and light fixture, as shown and described.

DESCRIPTION

FIG. 1 is a perspective view from below of the combination ceiling fan and light fixture in accordance with my design; FIG. 2 is an enlarged partial perspective view from below of the combination ceiling fan and light fixture in accordance with my design;

FIG. 3 is a bottom plan view of the combination ceiling fan and light fixture on a reduced scale in accordance with my design;

FIG. 4 is a front elevation view of the combination ceiling fan and light fixture on a reduced scale in accordance with my design;

FIG. 5 is a top plan view of the combination ceiling fan and light fixture on a reduced scale in accordance with my design; and,

FIG. 6 is a side elevation view of the combination ceiling fan and light fixture on a reduced scale in accordance with my design.

The front and rear elevation views are identical except for the position of the blades.

The side elevation views are identical except for the position of the blades.

The blades have been shown broken away in FIG. 2 for ease of illustration.
